PARAMETRIC AMPLIFIER USING CONDUCTING MAGNETIC MEMBER

Donald S. Rodbell, Burnt Hills, N.Y., assignor to General Electric Company, a corporation of New York
Filed July 26, 1965, Ser. No. 474,826
5 Claims. (Cl. 330—4.8)

This application is a continuation-in-part of my application Serial No. 65,085, filed October 26, 1960, and now abandoned, entitled "Magnetic Microwave Device" and assigned to the assignee of the present invention. The present invention relates to devices employing magnetic resonance and particularly to such devices as require large microwave magnetic field strengths.

A number of magnetic materials are known to display a magnetic spin resonance when magnetic energy is properly delivered thereto. Thus, a magnetized body will display an absorption of an applied radio frequency "pump" signal. As the frequency of the applied signal is varied a certain resonant frequency may be achieved at which R.F. power absorption is maximum. Bodies of such magnetic materials also exhibit conditions of "saturation" or near-saturation for an applied magnetic field where distinctly non-linear changes occur in the susceptibility of the material after certain levels of pumping power are applied at the resonant frequency. Therefore magnetically resonant elements are useful components of limiters, mixers, frequency converters and the like at the radio frequencies corresponding to resonance.

In one instance a parametric amplifier is possible including a magnetic body having considerable power applied at the pump frequency corresponding to the frequency of magnetic resonance. An R.F. input signal, also suitably applied to the magnetic body, can be made to mix with the pump signal and furthermore be amplified. An additional resonance is provided at an idling or difference frequency either by the magnetic element or associated apparatus.

Quite large R.F. magnetic field strengths are often required to produce these effects and hence these devices are conventionally regarded as high power devices where-in a small volume of magnetic material is disposed in a strong R.F. magnetic field established in a cavity resonator. Pump signals as large as 10 kilowatts peak power are typical at the microwave frequencies these magnetic devices prove most useful; such powers are not only expensive but in many cases difficult or impossible to generate, especially at frequencies above 10 kilomegacycles/second. In some instances pulsed magnetron equipment has been employed to produce such powers and then only for intermittent periods.

In accordance with a feature of the present invention a magnetically resonant element comprising a combination conducting and magnetic elongated body is oriented at a point of high electric field in an amplifier or mixer, whereby the body concentrates the energy of the incident electromagnetic wave to produce strong R.F. magnetic field effects in the body. A greatly improved coupling between incident energy at the frequency of magnetic resonance and the resonant magnetic material is produced compared with the energy coupling attained by placing a solely magnetic body at a point of high magnetic field. Power requirement reductions of several orders of magnitude are achieved.

2

According to another feature of the present invention the elongated filamentary element comprises a ferromagnetic monocrystalline iron whisker.

The subject matter which I regard as my invention is particularly pointed out and distinctly claimed in the concluding portion of this specification. The invention, however, both as to organization and method of operation, together with further objects and advantages thereof, may best be understood by reference to the following description taken in connection with the accompanying drawings wherein like reference characters refer to like elements and in which:

FIG. 1 illustrates magnetic spin resonance in a magnetized body;

15 FIG. 2 is a phantom view of a device illustrating the operating principles of the present invention;

FIG. 2a is a cutaway view of another device illustrating the operating principles of the invention;

20 FIG. 3 is an illustration of spin waves in a magnetic body;

FIG. 4 is a graph of frequency vs. wave number for the "normal" modes of a magnetic material;

FIG. 5 is an idealized plot of the magneto crystalline anisotropy field for iron vs. temperature;

25 FIGS. 6 and 7 are respectively isometric and cross-sectional views of a frequency "multiplier" according to the present invention;

FIG. 8 is a perspective view of a parametric amplifier according to the present invention;

30 FIG. 9 is a schematic illustration of charge excursion in the elongated conducting element according to the present invention; and

FIG. 10 is a plot of field vs. temperature for an iron whisker embodiment according to the present invention.

35 The theory and phenomena utilized by the present invention will be explained with reference to FIG. 1 depicting unpaired electrons 1 and 2 in a body of magnetic material disposed between a static external magnetic field represented by north pole 3 and south pole 4. The electrons spin with angular velocities around their own axis so that the electrons may be thought of as tiny magnetic dipoles or magnets producing a magnetic moment along their spin axis. In the event of a magnetic crystalline material disposed in the external magnetic field, the magnetic moments become aligned between the external poles.

40 If an outside force or source of energy is now applied to the magnetic material, the magnetic moments will tend to precess or oscillate about the original axis (between the external magnetic poles 3 and 4), their magnetic moments 5 describing a path thereabout as at 6. This precession motion is distinct from the electron spin motion. The precession will tend to occur at and define the resonant frequency of "uniform precession" for the magnetic material, and if the additional forces should

45 be in the form of an applied oscillating magnetic field 7 such a field will produce a greatly increased precession angle ϕ if the magnetic energy also oscillates at the resonant frequency of the uniform precession.

50 If the body of magnetically resonant material is disposed at a point of maximum magnetic field in an R.F. resonant cavity with R.F. energy at the cavity's frequency applied thereto, and if the cavity's frequency is the resonant frequency of the magnetic material then, theoretically, a large precessional angle ϕ will occur in the material. Non-linear operation and possible coupling will then result for an optimum precession angle and is at-

tributable to the resonant non-linear component of magnetization in the direction of the static field caused by the precession. Therefore, if two R.F. magnetic fields are applied to the magnetic material in FIG. 1, both perpendicular to the static field produced by poles 3 and 4, sum and difference field components will occur in the direction of the static field, if at least one of the incident fields produces a sufficient precession angle (ϕ) to result in the non-linear coupling operation.

Operation is preferably had at a precession angle near or approaching a saturation condition for the material.

Heretofore if a magnetically resonant material was employed as a non-linear electronic device, such magnetic element was often placed in an R.F. resonant cavity at a maximum magnetic field point in order to enjoy the strongest magnetic field strength available for a given incident R.F. power and thereby attain a maximum precession angle in the magnetic material. The material conventionally used was a magnetic ceramic body, for example, ferrite, and was non-conducting to allow maximum permeation of a magnetic field into the element.

However, in accordance with the present invention the magnetically resonant element has conducting properties as well as magnetic properties and furthermore, is disposed at a point of maximum electric field and generally parallel thereto rather than being disposed at a point of maximum R.F. magnetic field. The element is also preferably longer in the direction of the R.F. electric field than in the direction of the R.F. magnetic field and preferably of very small transverse dimension as depicted at 8 in FIG. 2, wherein a phantom view of a device illustrating the operating principles of the present invention is represented.

Referring to FIG. 2, the elongated filamentary element 8 according to the present invention is disposed in a space resonant device which may comprise a cavity 9 having a coupling iris 10 for introduction of electromagnetic radiation at the resonant frequency of the cavity. This electromagnetic radiation is also at a magnetically resonant frequency of filamentary body 8. The cavity 9 may be arranged to support the TE₀₁₂ mode such that the distribution of electric field is depicted by a sine wave 11 having a maximum electric field point at 12 and with which the filamentary body is vertically aligned. That is to say, the filamentary body is preferably disposed vertically and $1/4$ wavelength from end wall 13 of the cavity while being half way between the narrow vertical side walls of the cavity. The body may be supported in the cavity by any suitable insulating means, for example, a quartz tube (not shown). A static D.C. magnetic field is provided in a chosen direction with respect to the filamentary body 8, for example, by means of D.C. magnet 14 energized by an operating coil 15. The field is selected to produce magnetic resonance at the operating frequency and for the desired mode.

An alternative configuration is illustrated in FIG. 2a wherein the elongated element 8 is disposed along the electric field in a re-entrant cavity 9a. The electric field is quite strong in the center of this type of cavity. It is, of course, understood that other cavity configurations may be employed.

The elongated filamentary element 8 may be formed of suitable materials which are conducting and which exhibit magnetic resonance. The material should exhibit high permeability as well as reasonably low resistivity. One preferred form of such element is an elongated iron whisker being a single crystal of iron. Such material has the advantage of having a relatively narrow absorption line width and therefore is very advantageous in providing near-saturation conditions at relatively low incident pumping powers, in accordance with the formula:

$$H_{RF}^2 \doteq \frac{3(\Delta H)^3}{4\pi M_s}$$

where H_{RF} is the incident radio frequency field required

for saturation onset, ΔH is the absorption line width and M_s is the characteristic saturation magnetization of the body.

In addition, certain other materials may be suitably employed. For example, the elongated element may comprise a long thin wire formed of an alloy of about 80% nickel and about 20% iron frequently referred to as "Permalloy." Another exemplary material from which such a wire may be formed is a copper-cobalt alloy in which the cobalt content approximates 2% and is distributed as precipitate particles through a copper matrix.

Such an elongated body according to the present invention is also generic to a conducting wire having a magnetic coating or magnetic body disposed therearound.

With the elongated filamentary element according to the present invention it has been found possible to produce a given R.F. magnetic field strength with less than $1/1000$ the incident power heretofore employed for bringing about non-linear magnetic resonant conditions of a magnetic body disposed in an R.F. resonant cavity. This enhanced field produced in and by the elongated element of the present invention is further considered in connection with FIG. 9 where the elongated body is taken for convenience as a long thin cylinder having a length L , and the distance from the left hand end of which is designated as the variable x . In performing calculations of resultant magnetic field we first ask how much charge must one place on the ends of the body so that the applied electric field will be cancelled out along the surface of the body as it must be if the body is conducting. For convenience the center of the body is taken as a point where the field is cancelled. Then:

$$E_{(x)} = \frac{1}{4\pi\epsilon} \left[\frac{q}{x^2} + \frac{q}{(L-x)^2} \right]$$

where

$E_{(x)}$ is the voltage of point x ,
 ϵ is the dielectric constant of free space, and
 q is the charge taken to exist at each end of the body, and

$$E = \left(\frac{L}{2} \right) = \frac{2q}{\pi\epsilon L^2}$$

or

$$q = \frac{\pi\epsilon L^2}{2} E$$

The current due to the reversal of this charge excursion will be 90° behind q and E in time phase but in magnitude will be:

$$i = 2\pi f q = \pi^2 \epsilon L^2 f E_{max.}$$

in the maximum electric field, and at the surface of the body the R.F. magnetic field will be

$$H_{R.F.} = \frac{i}{2\pi r}$$

or

$$H_{R.F.} = \frac{\pi L^2 f}{2r} E_{max.}$$

where r is the radius of the body and f is the frequency of the applied signal.

Taking ω as $2\pi f$, the field

$$H_{R.F.} = \frac{\omega \epsilon L^2}{4r} E_{max.}$$

The ratio of this created field to the maximum magnetic field that would otherwise exist in the cavity then approximately equals:

$$\frac{\omega \epsilon L^2 Z_0}{4r}$$

where Z_0 is the ratio of maximum electric to maximum magnetic field.

Employing rationalized MKS units,

$$\epsilon = \frac{10^{-9}}{36\pi} \frac{\text{coulombs}}{\text{volt meter}}$$

and typically the ratio of maximum electric to magnetic field

$$Z_0 = 377 \text{ ohms}$$

Then for an X-band frequency of 10^4 megacycles = 10^{10} cycles per second,

$$\frac{H_{R.F.}}{H_{R.F. \text{ cavity max.}}} = \left(\frac{2\pi \cdot 10^{10} \cdot 10^{-9} \cdot 377}{36.4} \right) \frac{L^2}{r} = (52.35) \frac{L^2}{r}$$

This calculation should be taken as approximate.

Further, the incident power required for establishment of a given R.F. field is proportional to the square of the field. Therefore, the ratio of the power required to establish a given maximum field by means of the elongated element of the present invention, to the power required in the magnetic body as used heretofore, equals the square of the ratio of the fields produced by the two methods. Therefore the power required to produce a given R.F. magnetic field strength by means of the elongated element divided into that existent for a typical prior art magnetic body

$$= \left(52.35 \frac{L^2}{r} \right)^2 2740.5 \left(\frac{L^2}{r} \right)^2$$

It is noted that the field ratio is proportional to the square of the body length divided by its radius and since the power ratio is proportional to the square of the field ratio, this means that the power advantage gained is proportional to the 4th power of the element's length. It is then desirable to form the elongated filamentary element as long and thin as possible. A ratio of at least 10 to 1 of length over transverse dimension is preferred.

For a further exposition together with experimental findings regarding the above described effects, reference is made to the article "The Microwave Magnetic Field Near a Conducting Perturbation" by Donald S. Rodbell, Journal of Applied Physics, November, 1959.

The illustrative apparatus depicted in FIG. 2 (or FIG. 2a) may be employed with suitable additions as a mixing or amplifying device according to the present invention. For example, if the space resonant device of cavity 9 is rendered additionally resonant by means (not shown) at additional selected frequencies, the apparatus can be used as a parametric amplifier or as a mixer. For parametric amplification to take place three principal high frequency components are conventionally involved, i.e., a pump frequency f_p , the signal frequency f_s , and an idler frequency f_i equal to $f_p - f_s$. In the parametric amplifier the signal frequency is modulated or mixed with the pump frequency to produce the idler frequency. In turn, the idler frequency mixes with the pump frequency to produce the signal frequency again. If phase relationships are correct in the system's feedback, the signal current can be built up. Amplification is therefore obtained, or if the signal output is unloaded the system will oscillate.

In order to sustain such parametric amplification resonant circuits or meshes are provided at both the signal and idler frequencies while means are also provided for modulating both the signal frequency and idler frequency with the pump frequency.

In the FIG. 2 apparatus the elongated element 8 is driven into the non-linear resonance by the incident pump signal 11, admitted through iris 10. If the resonant cavity 9 is additionally resonant at the frequency of a signal f_s (also admitted into the cavity) and at the frequency of a suitable idler frequency at f_i , parametric amplification can result wherein a signal frequency of increased amplitude is retrieved or reflected from the cavity, and with the greatly decreased pumping power requirements as aforementioned, the pump signal driving the element 8 into a non-linear region in order to provide the mixing function.

The pump and signal frequencies may be admitted through iris 10. Alternatively, the element 8 may be extended through an aperture provided in the cavity with one or more high frequency currents externally excited therein.

- 5 Although thoroughly possible, it is sometimes difficult to render a single cavity resonant at a number of frequencies each with desired "Q." It is therefore frequently convenient to employ an element 8 which itself is responsive at one or more frequencies. One usual principal resonant frequency associated with a magnetically resonant element is the frequency of uniform precession conventionally referred to as the "uniform mode." When a magnetic resonant element is operating completely in the aforementioned uniform mode, all of its spinning electrons may be 10 thought of as precessing as shown by the precessional angle ϕ in FIG. 1, this being one state of such a system. However, the system may also sustain a spin wave phenomena between electrons in the crystal lattice of the magnetic body as illustrated in FIG. 3.
- 15 20 In FIG. 3 the various electrons continue to precess but their magnetic moments may be oriented at different angles with regard to one another throughout the crystal. These disorientations may be described as regular patterns throughout the crystal and are the so-called spin waves. If the system is non-linear, energy may be exchanged between spin waves and the principal or uniform mode. One spin wave's wave-fronts are illustrated by diagonal lines in FIG. 3 and the wavelength λ is indicated between two such wave fronts with the spin wave propagation direction being given by the long arrow. The 25 frequencies of spin waves which may exist in the magnetic sample are not proportional to the wavelength λ but take on a distribution as illustrated in FIG. 4, where the frequency is plotted against their individual wave number k equal to $2\pi/\lambda$, for a long, thin magnetic element. If the magnetic element will support appropriate spin waves as well as or instead of the uniform mode, one or more spin waves may be substituted for resonant frequencies of cavity 9 in the FIG. 2 apparatus. Spin waves 30 40 may also be driven by electromagnetic energy additionally provided to the cavity at spin wave frequencies. Thus the cavity 9 may be resonant at the pump frequency alone, depicted by wave 11, this frequency also being a frequency of precession in element 8, and wherein spin waves in element 8 are respectively employed at f_s and f_i for supporting parametric amplification. In like manner a principal precession and one spin wave or two spin waves may be employed in the element 8 with only one additional resonant frequency being provided by the 45 cavity.

50 55 Certain spin waves having low wave numbers are frequently spoken of as defining magnetostatic modes and the operation employing these modes spoken of as magnetostatic and semi-static operation.

It is understood that the various schemes applicable to parametric amplification are similarly applicable to the simpler case of a frequency mixer or converter.

The operating frequency of the principal precession called the uniform mode in a magnetic resonant element is given by the formula

$$\omega = \gamma = \frac{H_{\text{effective}}}{\gamma \cdot [H - (N_z - N_x)4\pi M_s] \cdot [H - (N_z - N_y)4\pi M_s]}^{1/2}$$

60 where

H is the "applied" external field (and in addition any crystalline anisotropy);

γ is the magneto mechanical ratio;

M_s is the characteristic saturation magnetization; and

N_x , N_y and N_z are demagnetization factors related to the shape of the magnetic element (for a generally ellipsoidal body).

70 75 This formula is applicable to the uniform precession when employed as the principal resonant mode in the elongated element according to the present invention. With the present invention more frequent use is made of the

electric or "curl" mode for the principal non-linearly driven mode as herein described. In the "curl" mode case, the demagnetization factors in the formula are those appropriate to a flat plate, i.e.

$$\omega = \gamma [H(H + 4\pi M_s)]^{1/2}$$

The frequency of usable spin waves in the element is given by the following formula:

$$\omega = \gamma [(H - N_z \cdot 4\pi M_s + ak^2) \cdot (H - N_z \cdot 4\pi M_s + ak^2 + 4\pi M_s \sin^2 \theta)]^{1/2}$$

where

a =a constant of the material and includes the exchange energy;

K =the wave number= $2\pi/\lambda$ and

θ =the angle at which the spin wave is propagating relative to the internal D.C. field direction, that is, relative to the average direction of the net magnetization.

The longer wave length spin waves are more affected by the shape of the magnetic element. For expressions of frequency for the magnetostatic modes, as well as the "uniform" mode, reference is made to R. L. Walker, Physical Review, vol. 105, (1957), page 390.

The frequency of principal curl mode precession in the conducting and magnetic elongated filamentary body according to the present invention, e.g., wherein the body is homogeneously conducting and magnetic throughout so that current and magnetic field are in effect limited to an outer skin depth of the elongated body, is given as previously stated by the following expression:

$$\omega = \gamma [H(H + 4\pi M_s)]^{1/2}$$

where

$H = H_{D.C.} + H_K$; and

$H_{D.C.}$ is the applied static magnetic field, and

H_K is a function of the material and is the magneto crystalline anisotropy "field."

For iron H_K is relatively large but depends upon the operating temperature. At room temperature the operating frequency according to the above formula, when applied to an iron whisker as described, is greater than 9 kilomegacycles and therefore if operation is desired in the X band or below, the apparatus employing the magnetic element should be desirably operated above room temperature. A relation between H_K and temperature for an iron whisker is plotted in FIG. 5. It should be noted that at higher frequencies this temperature of operation is substantially lowered.

The terminology "curl mode" comes from the Maxwell relation,

$$\text{Curl } \mathcal{H} = \mathcal{J} + \frac{\epsilon \partial \mathcal{E}}{\partial t}$$

where $\mathcal{J}$ is current density and $\partial \mathcal{E} / \partial t$ at the time rate of change of the electric field. This is a statement of the field produced around a conductor and the mathematical description "curl" is the origin of our nomenclature. That is to say, the charge flow or excursion in the conducting portion of the elongated element of the present invention produces a circular magnetic field therearound which is symmetrical around the axis of the element rather than being "uniform."

In FIG. 10, plots a and b represent respectively applied D.C. field vs. temperature for the curl mode and the uniform mode in an iron whisker, the frequency of the applied signal being held constant at an angular frequency which shall be designated ω_1 . The frequency of ω_1 in the particular test from which the curves a and b were drawn was 9 kilomegacycles. Curves c and d are plots of D.C. field vs. temperature for the curl mode and uniform mode in an iron whisker for a somewhat higher frequency, ω_2 . It may be readily appreciated that ω_2 can

be adjusted so that the uniform mode, d , for ω_2 will cross the curl mode, a , for ω_1 at a crossover point σ . That is, modes d and a are degenerate at this point and if one of them, preferably the curl mode a , is driven to non-linear operation, energy coupled into one mode will find its way into another in the same manner that energy coupled into the uniform mode or curl mode may find its way into the spin wave modes or vice versa.

In this manner both the curl and uniform modes in a single conducting magnetic element may be utilized to transfer energy from one frequency to another. A device employing this type of operation is illustrated in FIGURES 6 and 7 wherein the elongated conducting and magnetic element 17 extends through an aperture between a first waveguide or cavity 18 operating at ω_1 and a second waveguide or cavity 19 operating at ω_2 . Both waveguides preferably operate in the TE_{01} mode so that the elongated element 17 is disposed along the electric field of each guide or cavity and is preferably spaced a quarter of a wavelength from the shorted end of each guide or cavity so as to be at a point of maximum R.F. electric field in each. Electromagnetic energy in the guide or cavity 18 excites element 17 in its curl mode at ω_1 . The energy supplied waveguide or cavity 18 should be sufficient to drive element 17 to non-linearity. This situation allows the communication of energy to other possible modes; in particular mode d of FIG. 10 can be realized and the energy employed via guide 19. Other embodiments for employing both curl and uniform modes are readily suggested such as parametric amplifying devices, mixes, and the like, as hereinbefore disclosed. A principal feature is that at a low power expenditure at a frequency ω_1 one can obtain useful power at a frequency ω_2 . A cascaded system of these devices can be used to generate higher and higher frequencies by the frequency step-up conversion.

FIG. 8 illustrates a parametric amplifier configuration according to the present invention employing electromagnetic operation. Two frequencies, the signal frequency f_s , and the pump frequency f_p are applied through rectangular waveguide 20 to a bimodal cruciform cavity 21. A round coupling iris 22 located centrally with respect to both the bimodal cavity and the waveguide allows entrance of energy at both frequencies to the cavity. The cruciform bimodal cavity 21 is composed of a first rectangular section 23 resonant at the signal frequency f_s and a second rectangular section 24 perpendicular to the first, resonant at the pump frequency. Both sections 23 and 24 are oriented at an angle of approximately 45° with regard to the long wall of waveguide 20 and these sections 23 and 24 also have a common central area for central placement of iris 22 and also for housing a capillary tube 25 containing elongated conducting and magnetic element 26. The capillary tube 25 is also oriented at an angle of approximately 45° with respect to cavity sections 23 and 24 but is substantially perpendicular to the long wall of waveguide 20. The capillary tube is placed approximately one quarter wavelength (at the pump frequency, f_p) from the end wall opposite the coupling iris 22 and extends from one cruciform juncture diagonally across the central area of the cavity and out through a small aperture in the diagonally opposite cruciform juncture. Magnetic element 26, which has conducting and magnetic properties, extends from within the bimodal cavity out through the small aperture which receives the surrounding capillary tube 25 and is there encircled by a single turn coil 27 connected by means of leads 28 to a resonant circuit 29 tuned to an appropriate idler frequency, f_i . As before, the various frequencies are arranged such that $f_p = f_s + f_i$. The two resonant frequencies of cavity sections 23 and 24, that is, f_s and f_p respectively, are kept separate insofar as the ends of these sections are concerned in conjunction with waveguide dimensions by

means of a quartz mode separator 30 placed in one end of section 24.

The tuned circuit 29 may be any convenient resonant circuit tuned to an appropriate f_i and, for example, may actually comprise a butterfly-type tank circuit useful up to about 1,000 megacycles as described in the third edition of "Radio Engineering" by F. E. Terman, at page 434. Alternatively, this resonant circuit 29 may comprise an additional resonant cavity abutting the walls of cavity sections 23 and 24 having magnetic element 26 extending therein through a small aperture for receiving capillary tube 25. The alternative idler cavity will be more appropriate, of course, for higher idler frequencies. A static magnetic field longitudinal to magnetic element 26 is brought about by magnetic north pole 31 and south pole 32 disposed at either end of the capillary tube. The field thereof is appropriate to establish a principal resonant mode in element 26 at f_p .

In operation the apparatus of FIG. 8 functions to amplify the signal frequency f_s introduced into cavity 21 through waveguide 20 in that an incident frequency signal f_s is reflected out of the cavity in amplified form. The presented incident signal frequency initially establishes a standing wave pattern in cavity section 23 such that an electric field maximum is presented at magnetic element 26. The pump signal frequency f_p also presented through waveguide 20 excites cavity section 24 to resonance so that an electric field maximum of the pump signal is also presented at magnetic element 26. The pump signal, of course, is a local signal of much higher power and is raised to a level sufficient for driving element 26 into a non-linear region of operation near saturation. This is accomplished by the very enhanced magnetic field existing in element 26 in the principal or curl mode caused by electric field excitation thereof produced by electric charge excursions in the element. Further, since the element is operating non-linearly, the signal frequency electric field maximum also incident upon the element will couple and mix with the pump mode therein. It is noted that the signal frequency as well as the pump frequency both cause precession in the element 26 inasmuch as both frequencies result in magnetic field components which may be taken as perpendicular to the static magnetic field, in accordance with the arrangement of element 26 in the capillary tube whereby the element 26 is diagonally oriented to receive components of perpendicular excitation from both cavity portions 23 and 24. That is to say, element 26 has a component of its length parallel to each electric field (in cavity sections 23 and 24) and therefore both electric fields can cause precession in the element 26. The power of the pump frequency is preferably strong enough to cause a relatively large angle of precession and therefore due to the nonlinearity of the resultant magnetic field along the length of the element 26, a difference-frequency magnetic moment is built up along the length of element 26, equal in frequency to f_i , the idler frequency. Energy is coupled at the idler frequency to tuned circuit 29, which is tuned to the idler frequency. Energy is built up in the idler mode by means of tuned circuit 29 which, in turn, causes a longitudinally directed magnetic field in element 26 at idler frequency. This idler magnetic field in turn frequency modulates the magnetic precession in the element 26 mixes with the pump frequency f_p , producing an amplified output at the signal frequency f_s . In this manner, energy is transferred from the pump source at the frequency f_p to the signal frequency f_s . This signal is amplified and is re-delivered to wave guide 20 through aperture 22.

When a material is spoken of in this application as being magnetic, a material is meant which has a permeability substantially greater than one.

Similarly, a conducting material is taken to mean one having a resistivity substantially less than 10,000 micro ohm centimeters.

While I have shown and described several embodiments of my invention, it will be apparent to those skilled in the art that many other changes and modifications may be made without departing from my invention in its broader aspects; and I therefore intend the appended claims to cover all such changes and modifications as fall within the true spirit and scope of my invention.

What I claim as new and desire to secure by Letters Patent of the United States is:

1. A parametric amplifier comprising a hollow cruciform bimodal cavity having two mode portions supporting electromagnetic field distributions in orthogonal directions and provided with an aperture adjacent both said mode portions, an elongated member supporting electric conduction and for supporting a magnetic field which member exhibits non-linear magnetization, said member being angularly disposed in the central portion of said bimodal cavity with a major component of its length in a direction substantially parallel to electric field maxima in the electric field maxima in the central portion of said cavity and extending through said aperture, one mode of said cavity being resonant at an amplifier input frequency and another mode being resonant at a pump frequency, a second resonant system coupled to the extension of said member, and a D.-C. magnetic field acting upon said member for producing gyromagnetic resonance in said member so that said member magnetically resonates at the pump frequency of said cavity, said second resonant system resonating at an idler frequency whereby to provide parametric amplification in said cavity.
2. A parametric amplifier comprising a resonant waveguide cavity, input means coupling signal radio frequency energy to said cavity and pump radio frequency energy to said cavity to produce in said cavity an electromagnetic field distribution corresponding to each of said energies including electric field maxima and minima, said cavity being principally resonant at the frequency of at least one of said energies, an elongated member for supporting electric conduction and for supporting a magnetic field therealong which member exhibits non-linear magnetization disposed at a location of high electric field concentration in said cavity having at least a major component of its length aligned with the electric field distribution to provide an enhanced radio frequency magnetic field in said cavity and member, D.-C. magnetization apparatus producing a static magnetic field in said member for establishing gyromagnetic resonance therein at the frequency of said pump energy, said pump energy being provided at a power level sufficient to establish a large precessional angle in said member as a result of said enhanced radio frequency magnetic field, wherein precession around the transverse circumference of said member is substantially axially symmetric, and another resonance system coupled to said member for producing a magnetic field having a component axial to said member at a frequency equal to the difference between the frequency of said pump energy and the frequency of said signal energy whereby to provide amplification in said cavity at the frequency of said signal energy.
3. The amplifier according to claim 2 wherein said member is filament formed of electrically conductive and magnetic material, said filament having a length at least ten times its transverse dimension.
4. The amplifier according to claim 3 wherein said filament is a monocrystalline iron whisker.
5. A non-linear device comprising a resonant wave guide cavity, input means coupling first and second frequencies of radio frequency energy to said cavity at the same time to produce in said cavity and electromagnetic field distribution corresponding to each of said energies including electric field maxima and minima, an elongated member for supporting electric conduction and for supporting a magnetic field therealong which member exhibits non-linear magnetization, said member being disposed at a location of high electric field concentration in

11

said cavity having at least a major component of its length aligned with the electric field distribution to provide an enhanced radio frequency magnetic field in said cavity and member, and D.-C. magnetization apparatus producing a static magnetic field in said member for establishing gyromagnetic resonance therein at one of said frequencies, the energy at one of said frequencies being provided at a power level sufficient to establish a large precessional angle in said member as a result of
